UNITED STATES PATENT OFFICE.

JOAQUIN MORET GONZALEZ, OF MARCANE TERMINO, CUBA.

INJECTOR.

Application filed January 17, 1923. Serial No. 613,223.

To all whom it may concern:

Be it known that I, JOAQUIN MORET GONZALEZ, a citizen of Cuba, and residing at Marcane Termino, Municipality of Pala-
soriano, Oriente, Cuba, have invented cer-
tain new and useful Improvements in In-
jectors, of which the following is a specifi-
cation.

This invention relates to injectors for
steam boilers, particularly to those designed
for locomotives, and its principal objects
are to provide a novel form of injector in
which all of the interior parts, particularly
the check or delivery valve, are readily ac-
cessible and removable; to provide means
for positively seating the main steam valve
while the teaser or lifting valve is being
opened, and to provide novel means for
cleaning the injector and preventing the
deposit of mud or other residues and the
formation of scale. Other objects will be
apparent in the following description and
accompanying drawings.

In the drawings:

Figure 1 is a longitudinal vertical section
of an injector constructed in accordance
with my invention;

Figure 2 is a section on the line 2—2 of
Figure 1; and

Figure 3 is a section on the line 3—3 of
Figure 1.

The body portion or casing of the injector,
indicated at 10, is provided with the usual
steam inlet 11, water inlet 12, overflow out-
let 13, and delivery outlet 14. The various
inlets and outlets are suitably threaded to
facilitate the attachment of piping. The
casing is provided with various transverse
walls or partitions having aligned openings
therein to receive the combined forcing noz-
zle and delivery tube 15, the lifting nozzle
16, steam valve seat 17, and bonnet 18 for
supporting the valve actuating rod 19. The
diameters of these openings, and of the mem-
bers which fit therein, increase progressively
from front to rear of the casing, in order
that all of the above named parts may be
accessible from the rear of the casing, and
may be removed without disturbing the
piping or the connection of the casing to
the boiler. It will be noted that the check
valve 20 seats at 21 on the end of the de-
livery tube 15, and is supported in a guide-
way 22 threaded on the end of the tube 15.
Thus when the tube is removed the check
valve is removed with it. This greatly fa-

cilitates repair and adjustment of the check
valve, which is a moving part, and is usually
the most inaccessible member in an injector.

The main steam nozzle 23 is formed in-
tegral with the valve seat member 17, and
with the lifting nozzle 16, extending
through the latter and terminating just
within the rear end of the tube 15. A main
valve seat 25 is formed on the member 17
at the end of the steam nozzle 23, and an
auxiliary valve seat 26 is formed somewhat
to the rear thereof. The auxiliary valve 27
is rigidly secured to the valve rod 19 and
is made hollow to contain the main valve 28,
which projects beyond the auxiliary valve
so that both valves may in closed posi-
tion at the same time. The main valve has
a limited sliding movement within the aux-
iliary valve whereby the auxiliary valve
may be opened without unseating the main
valve. A lip 27^a engages a lip 28^a to unseat
the main valve after the auxiliary valve has
moved a predetermined distance, and a
spring 30 interposed between the main valve
and the rod 19 serves to keep the main valve
positively seated until after the auxiliary
valve is fully opened.

The transverse walls or partitions divide
the casing into a lifting or suction chamber
31, a water chamber 32, and an overflow
chamber 33, the latter being provided with
the usual overflow poppet valve 34 opening
into the overflow pipe 35. A stem 36 is pro-
vided for positively seating or locking the
overflow valve when so desired for certain
operating conditions, as is well known. The
usual communication between the forcing
tube and the overflow chamber is provided
in the present invention by the radial ducts
15^a in the tube 15.

The water chamber and the overflow
chamber communicate with each other
through the passageway 37, and have a com-
mon outlet 38 into the overflow pipe 35. 100
This communication and this outlet are
adapted to be closed by a unitary drainage
valve 39 which seats at 40 and 41. The
valve 39 is supported on and actuated by a
valve rod 42 sliding in a sleeve passing 105
through the suction chamber 31.

An operating handle 43 for the steam and
drainage valves is pivoted to the fulcrum 44
which is in turn pivoted to the casing 10.
The valve rod 19 and the link 45 connected
to the valve rod 42 are pivoted to the handle
43 on opposite sides of the fulcrum, so that

as the steam valve is opened, the drainage valve is closed, and vice versa. A segment 46 is rigidly secured to the rod 19 and provided with notches for engagement with a spring actuated pawl 47. When the handle is manipulated the pawl slides over the segment and engages the notches, which act as stops to prevent the handle from being inadvertently moved too far. The contour of the pawl and notches is such, however, that the handle can be pulled past any notch by the application of a moderate force.

Water may pass from the water inlet 12 into the suction chamber through an opening 48 controlled by a valve 49 operated by a hand wheel 50.

The operation of my injector is as follows: When it is desired to start the injector, the valve 49 is opened to admit water to the suction chamber 31, and the handle 43 is pulled back until the pawl engages the notch 51. This opens the auxiliary steam valve 27 and admits steam to the passages 52, the main valve being held tightly closed by the spring. Jets of steam issuing from the passages 52 enter the suction or lifting nozzle 16, creating suction as is well known, and lifting water into the suction chamber 31. When water appears at the overflow, the handle 43 is pulled clear back, opening the main steam valve 28 and closing the drainage valve. Valve 28 admits steam to the nozzle 23, and the jet of steam issuing from this nozzle causes the well known injector action, forcing water through the check valve against the boiler pressure. To stop the injector, the valve 49 is closed and the handle 43 moved forward until the pawl engages the notch 53. In this position the drainage valve opens the chambers 32 and 33 to each other and to the atmosphere, but the main steam valve is still open. The powerful jet of steam issuing from the nozzle 23 blows out the chambers 32 and 33, ejecting all mud and residues through the passage 38, and leaving no water standing in the chambers to form scale. When the blowing out operation is completed the handle is moved forward, closing the steam valves.

It is to be understood that the invention is not limited to the particular details of construction described for the sake of illustration, but includes such changes as come within the scope of the appended claims.

Having thus described the invention what is claimed as new and desired to be secured by Letters Patent is:

1. In an injector, in combination, a main steam nozzle, an auxiliary steam nozzle, a valve for admitting steam to each of said nozzles, means for successively opening said valves, and means interposed between the main valve and the auxiliary valve for positively seating the main valve while the auxiliary valve is being opened.

2. In an injector, in combination, a main steam nozzle, an auxiliary steam nozzle, a valve for admitting steam to each of said nozzles, means for successively opening said valves, and a spring interposed between said means and the main valve to hold the main valve positively seated while the auxiliary valve is being opened.

3. In an injector, in combination, a steam valve, a forcing tube, a casing surrounding the forcing tube, an outlet for said casing, means for closing the outlet when the injector is operating, and means for simultaneously opening the outlet and admitting steam to said casing to eject residues therefrom.

4. In an injector, in combination, a steam valve, a forcing tube, a water chamber and an overflow chamber surrounding said tube and communicating with each other, and means for automatically closing the communication when the steam valve is opened.

5. In an injector, in combination, a steam valve, a forcing tube, a casing surrounding the tube and having a water chamber open to the atmosphere and an overflow chamber communicating therewith, and a single valve for closing the communication between the chambers and the opening to the atmosphere when the steam valve is opened.

In testimony whereof I hereunto affix my signature.

JOAQUIN MORET GONZALEZ.
